UNITED STATES PATENT OFFICE

127,500

DESIGN FOR AN ELECTRIC CONTACT THERMOMETER

Ernest J. Heldmann, Rochester, N. Y., assignor to Taylor Instrument Companies, Rochester, N. Y., a corporation of New York

Application April 4, 1941, Serial No. 100,125

Term of patent 14 years

To all whom it may concern:

Be it known that I, Ernest J. Heldmann, a citizen of the United States of America, residing at Rochester, county of Monroe, State of New York, have invented a new, original, and ornamental Design for an Electric Contact Thermometer, of which the following is a specification, reference being had to the accompanying drawing, forming a part thereof, wherein:

Fig. 1 is a front view of an electric contact thermometer, showing my new design;

Fig. 2 is a side view; and Fig. 3 is a rear view thereof, portions of the thermometer in each of said views being broken away.

I claim:

The ornamental design for an electric contact thermometer, as shown.

ERNEST J. HELDMANN.
